COMBINED HELICOPTER AND AEROPLANE

Anthony V. Santarsiero, Bronx, N. Y., assignor
of one-half to George Pall, New York, N. Y.Application September 23, 1931, Serial No. 564,687
Renewed June 19, 1933

7 Claims. (Cl. 244—15)

This invention relates to a combined helicopter and aeroplane.

An object of the invention is the provision of an aeroplane having incorporated therein means for elevating the plane directly above the spot where it rests, thus eliminating long runways and for permitting the plane to be landed from points overhead.

Another object of the invention is the provision of an aeroplane having an air tunnel having a driven propeller at the forward open end for forcing air through the tunnel which acts upon a motor which in turn drives a pair of propellers located at the front of the aeroplane and co-operating with the main central propeller for propelling the vehicle.

A further object of the invention is the provision of an aeroplane in which a clutch mechanism is adapted to connect or disconnect the main propeller from the engine.

A still further object of the invention is the provision of an aeroplane equipped with wheels and pontoons, the wheels being cushioned by means of springs and movable towards the fuselage so that when the pontoons are being employed the wheels will be in an inoperative position and will not interfere with the supporting of the plane by the pontoons.

Another object of the invention is the provision of horizontally disposed propellers located adjacent openings of the wings of the aeroplane which co-operate with movable vanes in adjacent openings in the wings for aiding in elevating or lowering the plane in a substantially vertical line.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention as expressed in the appended claims.

In the drawings:

Figure 1 is a front view in elevation of an aeroplane constructed in accordance with the principles of my invention.

Figure 2 is a fragmentary horizontal section taken along the line 2—2 of Figure 1.

Figure 3 is a vertical section through the cushioning supporting means for the wheels.

Figure 4 is a top plan view of the aeroplane.

Figure 5 is a plan view of a propeller when the

aeroplane is operated by elevating or lowering the plane under helicopter principles.

Figure 6 is a transverse vertical section taken along the line 6—6 of Figure 5.

Figure 7 is a transverse vertical view taken along the line 7—7 of Figure 5.

Figure 8 is a fragmentary longitudinal vertical section taken along the line 8—8 of Figure 1.

Figure 9 is a reduced longitudinal view of the 65 aeroplane, and

Figure 10 is a transverse vertical section taken along the line 10—10 of Fig. 1.

Referring more particularly to the drawings, 20 and 21 designate the wings of a biplane which extend laterally from a fuselage 22 which includes a cockpit 23 in which the controls are located for actuating the various mechanisms by which the aeroplane is governed. An engine 24 is mounted in any approved manner at the forward end of 75 the fuselage.

A main propeller 25 is driven by the engine and is connected or disconnected from said engine by a clutch mechanism 26 controlled by a lever 27, a link 28 and an operating handle 29. 80

A shaft 30 is driven by the engine 24 and has a gear 31 secured thereto in mesh with a gear 33 which is secured to a shaft 34. This shaft drives a gear 35 in mesh with a gear 36 which is fixed to a shaft 37. The shaft 37 in turn drives a 85 propeller 38 located at the forward open end 39 of an air tunnel 40.

A wind motor, generally designated by the numeral 41, is secured to a sleeve 42 mounted on the shaft 37 so that the sleeve is rotatable independently of said shaft. A gear 43 is secured to the sleeve 42 and meshes with a gear 44 secured to a shaft 45. This shaft extends downwardly through the lower wing 20. 90

A gear 46 secured to the lower end of the shaft 45 meshes with a gear 47 which is secured to a shaft 48. A gear 49 is secured to the shaft 48 and meshes with a gear 50 secured to a shaft 51. This shaft extends longitudinally of the wings and a gear 52 secured to the shaft 51 meshes with a gear 53 secured to a propeller shaft 54. Said shaft drives a propeller 55 located at the right hand end of the aeroplane as shown in Fig. 1. A similar set of intermeshing gears 52^a and 53^a drives a propeller shaft 57 which is connected to the shaft 56 by the intermeshing gears. 100

It will be noted from an inspection of Figs. 2 and 4 that the upper wing 20 is provided with openings 60 and 61 over which are adapted to be revolved lifting propellers 62 and 63, respective- 110

ly. The propeller 62 is driven by a shaft 64 while the propeller 63 is driven by a shaft 65.

The wing 21 is provided with openings 66 and 67 located at opposite sides of the fuselage 22 over which are revolved propellers 68 and 69, respectively. The propeller 68 is secured to the shaft 64 while the propeller 69 is secured to the shaft 65.

A gear 70 is secured to a shaft 30^a and meshes with a gear 71 secured to a shaft 72. The last-mentioned shaft extends through the fuselage 22 and towards the left portion of the wing 21 and a gear 73 secured to the outer end of the shaft 72 meshes with a gear 74 which is secured to the shaft 64.

A gear 75 is secured to the shaft 76 and meshes with the gear 70 which drives a gear 77 meshing with a gear 78 secured to the shaft 65.

A clutch mechanism 80 is adapted to connect or disconnect the shaft 30^a with the shaft 30. A lever 81 operates the clutch mechanism through a link 82 connected to a hand lever 83 which is adjacent the cockpit.

A clutch mechanism 85 is operated by an arm 86, a lever 87, a link 88 and a hand lever 89 located adjacent the cockpit and within easy reach of the aviator.

On opposite sides of the openings 60 and 61 in the wing 20 are located elongated openings 90 and 91. Each of the openings is closed by vanes 92 or 93. These vanes are hingedly mounted at 94 intermediate the side walls of the openings and are controlled by springs 95 for maintaining the vanes closed. Cables 96 are connected to the vanes 92 and in turn these cables are connected to a single cable 97 which is trained over a pulley 98. A cable 99 is connected to the cable 97 at 100 and extends inwardly to the cockpit where it may be operated by the aviator.

A second cable 101 extends from the cockpit, to which is secured, at 102, a cable 103 trained over an idler pulley 104. A pair of cables 105 extend upwardly from the cable 103 and are connected to the vanes 93. The cable 99 extends over an idler pulley (not shown) which is in line with the pulley 98 and a pair of cables extend downwardly, as shown at 106, and are connected to a pair of vanes 107 which are hingedly mounted on the left portion of the wing 21 and are maintained in closed position by means of springs similar to the springs 95 as shown in Figs. 1 and 4 for maintaining the vanes in position.

A pair of vanes 110 located at the right hand end of the wing 21 for closing openings 111, shown in dotted lines in Fig. 1, are hingedly mounted and are normally maintained in closed position by springs (not shown). Cables 112 are connected to the vanes 110 and extend over an idler pulley, not shown, which is in alignment with the pulley 104 and are connected to the cable 101 as shown at 102.

The bottom of the wing 21 is provided with pontoons 120 located upon opposite sides of a pair of supporting wheels 121 and are carried by struts 122.

The wheels are supported by an axle 125 which is carried by rods 126 movable through the base member 127 of a U-shaped bracket 128 which is secured to a hinge 129 carried by the underface of the wing 21. The upper ends of the rods 126 are rigidly secured to a cross head 130 and springs 131 maintain the cross head 130 normally in engagement with the bottom member 127 of the bracket 128, thereby permitting the wheels and

the cross head 130 to move inwardly, thereby reducing shocks to the aeroplane.

When the wheels are in their normal operative position the longitudinal side edges of the bottom 127 of the bracket 128 rest upon flanges 132 carried by arms 133 which are secured at 134 to the underface of the wing 21. When it is desired, however, to move the wheels 121 to an inoperative position in order to permit the pontoons 120 to rest upon the surface of a body of water, it is only necessary to exert a pull on a rod 140 whereby the base member 127 of the bracket 128 is moved out of engagement with the flanges 132 and the wheels are moved inwardly and out of a position where they would interfere with the operation of the pontoons.

The wings as is usual are provided with ailerons 145, a rudder 146 and elevators 147 and these last-mentioned elements are controlled in the usual manner and therefore their operating mechanism which forms no part of the present invention are not disclosed.

The operation of my device is as follows: The engine is started in any approved manner and when the clutch 26 is properly actuated through the lever 29 and the propeller 25 is connected with the engine and the aeroplane is ready for flight. However, the clutch member 85 is shifted to connect the shaft 34 with the shaft 30 whence the propeller 38 will be driven and since this propeller forces air through the air tunnel 40 the wind motor 41 will be driven, thereby operating the shaft 45, the shafts 48 and 51, so that the auxiliary propellers 55 and 57 will likewise be driven and will aid in pulling the machine forward.

It will also be noted that after the propeller 38 is driven it will also aid in the pulling movement of the plane.

When it is desired to elevate the plane directly 115 above the ground, the clutch mechanism 80 is operated so that the shaft 30^a will be driven and likewise gears 70, 71, and 75. Therefore, the shafts 72 and 76 will be driven and likewise shafts 64 and 65 for causing rotation of the propellers 120 68 and 69 and likewise the propellers 62 and 63 in the direction indicated by the arrows in Figs. 2 and 4. It will be noted that these propellers move in opposite directions or inwardly towards each other and they are so constructed that 125 they will tend at all times to drive the air downwardly in order to elevate the plane.

As an additional aid in elevating the plane the cables 99 and 101 are actuated, thereby opening the vanes 92, 93, 107 and 110. The opening of 130 these vanes reduces the resistance of the air on the wings 20 and 21 so that as the propellers previously mentioned are operated in the directions indicated by the arrows, the plane will be elevated. It will be appreciated also that the plane 135 by the control of the propellers of the helicopter type will also permit the plane to be lowered at will from a vertical without requiring long runways for the purpose.

Referring more particularly to Figs. 5 to 7, 140 inclusive, it will be seen that the propeller, designated by the numerals 62, and which is representative of the type of the other lifting propellers 63, 68 and 69, is constructed in a different manner from the main propeller 25 or the auxiliary propellers 55 and 57. These propellers have a narrow width, as shown at 170, where they are connected to a hub 171. They are expanded until the greatest width, shown at 172, appears at 145 their outer ends. The blades of the propellers 150

have a slight twist so that the air will be forced downwardly and they will all act simultaneously for lifting the aeroplane directly from the ground and in a vertical plane.

5 It will be appreciated that the invention thus described has been applied to a biplane but the several operating devices may be equally well adapted for use on monoplanes. When the invention is so employed only one set of vanes will be necessary to close a pair of elongated openings in each single wing and only one set of cables will be necessary to operate these wings. Furthermore, there will be only one pair of circular openings over which will be placed the propellers similar to the propellers numbered 68 and 69.

I claim:

1. In a combined helicopter and aeroplane having openings in the wings thereof, propellers mounted for rotation above said openings for aiding in lifting the aeroplane directly off the ground, means for driving said propellers, the wings having elongated openings adjacent the first-mentioned openings, a pair of hinged vanes for each of the elongated openings, and means for simultaneously operating all of the vanes, the vanes being hingedly mounted longitudinally and centrally of the openings, the free ends of the vanes at an opening being located in opposite directions from each other.

2. In an aeroplane, an engine, a main propeller driven by the engine, a wind tunnel supported centrally on a wing and having an open front end, a propeller at the open end, means for driving the last-mentioned propeller from the engine, a wind motor in the tunnel and operated by the air passing through said tunnel, an auxiliary propeller located at each side of the main propeller, means operatively connecting the wind motor with the auxiliary propeller.

3. In an aeroplane, an engine, a main propeller driven by the engine, a wind tunnel supported centrally on a wing and having an open front end, a propeller at the open end, means for driving the last-mentioned propeller from the engine, a wind motor in the tunnel and operated by the air passing through said tunnel, an auxiliary propeller located at each side of the main

propeller, means operatively connecting the wind motor with the auxiliary propeller, and means for connecting or disconnecting the second-mentioned propeller and the engine.

4. In an aeroplane, an engine, a main propeller driven by the engine, a wind tunnel supported centrally on a wing and having an open front end, a propeller at the open end, means for driving the last-mentioned propeller from the engine, a wind motor in the tunnel and operated by the air passing through said tunnel, an auxiliary propeller located at each side of the main propeller, means operatively connecting the wind motor with the auxiliary propeller, the last-mentioned means including means for disconnecting the auxiliary propellers from the engine.

5. In a combined helicopter and aeroplane having openings in the wings thereof at opposite sides of the fuselage, the opening in one wing being aligned with opening in the other wing, a lifting propeller mounted above each opening, a vertically disposed shaft located axially of a pair of aligned openings at each side of the fuselage, the propellers above a pair of the aligned openings being secured to the shaft located axially of the openings, an engine, means operatively connecting the shafts with the engine, auxiliary propellers located forwardly of the lifting propellers and confined between horizontal planes passing through the wings of the aeroplane.

6. In a combined helicopter and aeroplane having a pair of elongated openings in each wing, vanes hingedly mounted in the openings, the hinged edges of the vanes in each wing being adjacent to each other, and means for moving the vanes to an open position.

7. In a combined helicopter and aeroplane, a propeller, an engine for driving said propeller, auxiliary propellers, a wind tunnel having the opposite ends thereof open, means connected with the engine for driving air through said tunnel, a motor in the tunnel and actuated by the air passing through said tunnel and operatively connected with the auxiliary propellers, and means for controlling actuation of the auxiliary propellers and included in the connections between the air driving means and the engine.

ANTHONY V. SANTARSIERO.
